THERMIONIC TUBE

Philip F. Scofield, Palo Alto, Calif., assignor to
Heintz & Kaufman, Ltd., San Francisco, Calif.,
a corporation of Nevada

Application July 18, 1932, Serial No. 623,115

2 Claims. (Cl. 250—27.5)

My invention relates to a thermionic tube having a variable amplification factor, and more particularly to such a tube in which a wide ribbon filament is positioned between a control electrode and the anode, the flat surface of the ribbon being at right angles to the plane of the control electrode.

Among the objects of my invention are: To provide a thermionic tube having a variable mu-factor or amplification factor; to provide a variable mu tube of simple and economical construction; to provide a thermionic tube having a mu-factor which varies from point to point of the cathode emissive surface; and to provide a variable mu tube designed for the elimination of distortion in radio receiving sets.

Other objects of my invention will be apparent or will be specifically pointed out in the description forming a part of this specification, but I do not limit myself to the embodiment of my invention herein described, as various forms may be adopted within the scope of the claims.

Referring to the drawing:

Figure 1 is a view, partly in section and partly in elevation, of a vacuum tube embodying this invention.

Figure 2 is a cross sectional view taken in the plane indicated by the line 2—2 in Figure 1.

Figure 3 is a longitudinal section of the elements alone, taken in a plane indicated by the line 3—3 in Figure 2.

In broad terms my invention comprises a thermionic tube having an anode and control electrode, preferably located in parallel planes. A cathode comprising a wide ribbon filament is positioned between the electrodes, with one narrow edge close to and parallel to the control electrode. The major surface of the ribbon is preferably at right angles to the plane of the control electrode.

In the drawing, which represents a preferred embodiment of my invention, a bulb 1 is provided with a reentrant stem 2. All of the support wires are sealed into a pinch 4 and some of them are extended through the stem in order to make connection to the base after exhaust.

An anode 5, and a control electrode 6, are supported respectively by the anode supports 7 and the control electrode supports 9. One of each of these supports may be a dummy, or a support which does not extend all the way through the pinch.

The anode and control electrode are preferably formed as flat plates, provided with flanges 10

for stiffening purposes, and made of nickel, or tantalum. It is customary to fasten such plates to the support wires by electric welding.

A bridge support 11 extends upwardly from the top of both anode and control electrode and is inserted into a filament bridge 12 of insulating material such as lava or isolantite, which serves both to space and maintain the plates 5 and 6 parallel, and to provide a bearing hole 14 through which is placed a filament hook 15. The shank 10 of this hook is inserted into an extension spring 17 fastened to the shank by the weld 19.

Filament leads 20, both extending through the pinch, are spread apart, and welded to the ends of a wide inverted V-shaped ribbon filament 21 which has its apex 22 caught by the filament hook 15 so that the entire filament is firmly held in tension by the spring 17.

The filament leads 20 are bent and adjusted until one narrow edge of the ribbon is close to 20 the control electrode and equally spaced from it. At the same time the wide surface is positioned at right angles to the plane of the control electrode.

After these adjustments have been made the tube is exhausted and sealed off the pumps in the usual manner, and provided with a base 24. The lead wires 25 coming from the electrodes are inserted into base prongs 26 in the customary order and secured to the prongs by soldered joints 27.

In operation as used in conjunction with the proper circuits to take advantage of its variable mu characteristics, the control electrode will have a high degree of control over the emission from that portion of the ribbon closest to the electrode, and a lesser degree of control over the emission from the far portions of the cathode ribbon. The variation of mu-factor may be increased by increasing the width of the ribbon.

I am aware of the fact that ribbon filaments have been used in ordinary tubes in edge relation to the electrodes, but in all such cases the ribbon has been made very narrow so that uniform control might be had of all the emission. I deliberately utilize a wide ribbon, and with such wide ribbons a wide variation in mu-factor may be obtained. The advantages of a high amplification factor are retained at normal voltages, while at high biases, the low distortion characteristics of a low mu tube are automatically obtained, thus providing a tube having minimum distortion.

While my invention is described as being adapted to three-element tubes, it is obvious that the same general results and advantages will be obtained when used in conjunction with tubes hav-

ing additional control, accelerating or shielding electrodes.

I claim:

1. A thermionic tube comprising an anode, a control electrode and a cathode having a flat emissive surface interposed between said anode and control electrodes, and having its narrow edge closely adjacent and parallel to the control electrode.

2. Means for producing a variable mu factor in a thermionic tube comprising an anode, a control electrode, and a wide ribbon filament interposed between said anode and cathode, one narrow edge of said ribbon being closer to said control electrode than the other narrow edge.

PHILIP F. SCOFIELD.
